HAND-OPERATED KNITTING MACHINE
Kojo Sasaki, Narumi-cho, Aichi-gun, Aichi-ken, Japan,
assignor to Nihon Misin Seizo Kabushiki Kaisha,
Nagoya, Japan, a corporation of Japan

Filed Apr. 19, 1961, Ser. No. 104,061
6 Claims. (Cl. 66—68)

This invention relates to a hand-operated knitting machine, and more particularly to a hand-operated knitting machine having an elongated flat bed.

Hand-operated knitting machines have been known in the art which comprise single elongated flat needle bed, a plurality of needles arranged in a row capable of advancing and retracting at a right angle with respect to the lengthwise direction of said bed and having their butts projecting above the top of the bed and a carriage mounted as to be slidable longitudinally of said bed and provided with a yarn guide at the front thereof and on the bottom side with cam means for engaging the butts of the needles during knitting operations to cause the advance and retraction of said needles.

In such knitting machines, however, when it was desired to perform knitting other than plain knitting, for example, fancy knitting such as multicolor knitting or tucking, it was necessary to select the butts of the needles with which knitting one color yarn in multicolor knitting or tucking was to be performed and advance them individually by hand to keep them separate from the other needles used in the knitting operation. Hence, in knitting knitted products such as mentioned above, much time was expended with a great tendency to make mistakes.

A primary object of the present invention is to make it possible to knit fancy knitted products with precision in a short time. For achieving this object, the hand-operated knitting machine of this invention comprises a plurality of needles whose shanks project into a needle bed, means for lowering the rear end of the shank of the needle perpendicularly to the upper flat surface of said needle bed when any of said needles is advanced to a somewhat more forward position for participation in knitting operations from its nonparticipating position, at least one needle selecting member mounted in a supporting frame secured to the aforesaid needle bed which is capable of reciprocation parallel to the advancing and retracting direction of the needles and is of a length capable of acting on all of the needles, means for causing the reciprocation of said needle selecting member, and needle selecting projections provided at suitable intervals along said needle selecting member. Thus, in accordance with this invention, when the needle selecting member is advanced it becomes possible to select and advance in a single stroke from the needles that are participating in the knitting operation those whose shanks come opposite the needle selecting projections as arranged and in engagement therewith.

Another object of the invention is to provide a wide variety in the possible arrangements of the knitting needles that are selected and advanced by the aforesaid needle selecting member, thereby obtaining a wide variety of knitted patterns both readily and rapidly. To attain this object, in the hand-operated knitting machine of the present invention the aforesaid needle selecting member consists of a plurality of pattern plates having numerous needle selecting projections disposed at regular intervals from each other, whereby a wide variety of arrangements are possible by changing or combining said pattern plates.

A further object of the invention is to provide an easily operated hand-operated knitting machine in which the change in the arrangement of the needle selecting projec-

2

tions as described above is readily accomplished. For achieving this object, the invention comprises means for positioning the needle selecting projections of the aforesaid pattern plates normally in their inoperative positions in which they do not engage the rear ends of any of the needle shanks, manually operable actuating members supported by the aforesaid supporting frame and of the same number as the number of pattern plates to which each is coupled, means for bringing each pattern plate connected to an actuating member into operative position so that its needle selecting projections are engageable with the rear ends of the needle shanks of these needles participating in the knitting operation when the aforesaid actuating member is actuated, a locking device for holding in their operative positions the pattern plates coupled to the actuating members by locking said actuating members in their actuating positions, and means for releasing said locking device and returning the aforesaid pattern plates to their inoperative positions. By the very simple operation of manually moving the aforesaid actuating member to its actuating position the arrangement of the pattern plate can be changed concurrently with its being brought into its operative position.

Other objects and advantages of the invention will be apparent from a consideration of the description given hereinafter and the accompanying drawings.

FIGS. 1 to 7 illustrate an embodiment of the present invention, FIG. 1 being a top plan view of the essential parts of a hand-operated knitting machine of the invention.

FIG. 2 is a top plan view, on an enlarged scale, of the essential parts of the invention with a part of the needle bed and cover cut away and a part shown in section.

FIG. 3 is a sectional view taken along line III—III of FIG. 2.

FIG. 4 is a view illustrating the needle selecting member.

FIG. 5 is a sectional view taken along line V—V of FIG. 2.

FIG. 6 is a sectional view taken along line VI—VI of FIG. 2.

FIG. 7 is a sectional view, on an enlarged scale taken along line VII—VII of FIG. 2.

A preferred embodiment of the invention will be described in detail with reference to FIGS. 1 to 7. 1 is the elongated supporting frame which consists of a cover 1a to which has been secured a reinforcing frame 1b. 2 is the single elongated flat needle bed which has been secured to said supporting frame 1. 3 are the needles which have been mounted in the aforesaid needle bed in parallel alignment so as to be advanced and retracted in a direction at a right angle to the lengthwise direction of said bed, the butts 4 of said needles projecting above the top of the needle bed, and the shanks 5 of the needles projecting to the back of said needle bed. 6 is the rear side supporting plate whose one edge is secured to the rear of said needle bed 2 on its underside with its other edge secured to the supporting frame 1, and is for supporting the shank 5 of the aforesaid needles 3.

Immediately to the rear of the butts of each of the aforesaid needles 3 there is provided an inclined portion 7 in the shank 5. When, as shown in FIG. 3 by the broken line, the needle is at its backmost position of the needle bed where it does not participate in knitting operations, its inclined portion 7 is in the rear of the aforesaid rear side supporting plate 6, and the rear end of the shank 5 rises upward, whereas when the needle 3 is in a somewhat more forward position than in the above instance—a position, as shown by the solid line in the same figure, where it participates in knitting operations—the aforesaid inclined portion 7 is in a position to the front of said rear side supporting plate 6, and the rear

end of the shank 5 lowers. That is, there is a difference in the heights of the rear ends of the shanks 5 of the needles 3 which participate in knitting operations and those which do not.

8 is the carriage mounted on the needle bed 2 which is manually slideable along the lengthwise direction of said needle bed 2. At its front is provided a yarn guide 9 and a pair of pressers 10, 10. On the underside of carriage 8 is provided cam means (not illustrated) which engages the aforesaid butts 4 of the needles 3 and effects the advancing and retracting movements of said needles.

11 is the holder forming a U-shaped channel 12 along practically the whole length of the needle bed 2. It is located underneath and to the rear of the needles 3 that are participating in knitting operations, and on its underside several guide studs 14 are attached, each of which passes through several guide slots 13 which are disposed parallel to the direction of the advance and retraction of the needles 3 and are suitably spaced along the length of said reinforcing frame 1b. Thus, the aforesaid holder 11 is capable of making reciprocating movements paralleling the direction of advance and retraction of the needles 3.

As shown in FIG. 2, L-shaped levers 15 (only one shown) are pivotally attached to the underside of the aforesaid reinforcing frame 1b at three places, one approximately at the middle and the other two at the end portions of said frame. At the tip of one of the arms of the lever 15a a long groove 16 is provided paralleling the longitudinal direction of said arm, whereas on the other arm 15b a projection 17 is pivotally attached so as to be rotatable. The tip of the aforesaid arm 15a extends under the aforesaid holder 11 where the groove 16 of said arm 15a engages a pin 18 provided in the underside of said holder 11. The tip of the arm 15b is extended so as to be still further back than the shank 5 of the needles 3, and each of the projections 17 is secured by way of stop screws 21 to a rod-like link 20 whose one end has a crook 19. Between the aforesaid holder 11 and the reinforcing frame 1b a spring 22 for pressing the aforesaid holder 11 to the rear is provided.

Inasmuch as the construction is as above described, when the aforesaid link 20 is pulled to the right in its lengthwise direction facing FIG. 2, the aforesaid levers 15 are turned in unison, and the aforesaid holder 11 is made to advance in a direction paralleling the direction of advantage and retraction of the needles. When the link 20 is released, the holder 11 reverts to its former position.

23a-23d are the four pattern plates that are of lengths sufficient to act on all of the needles and are held in the groove 12 of the aforesaid holder 11 and move together therewith, thereby constituting a single needle selecting member. As shown in FIG. 4, each of these pattern plates 23a-23d has provided along its upper edge a number of needle selecting projections 24a-24d spaced at intervals four times the pitch of the needles 3, the pitch being the distance between adjacent needle, and at one end, separated a somewhat greater distance from the needle selecting projections, and likewise at the upper edge, are provided engaging recesses 25a-25d. These pattern plates 23a-23d are further provided with several L-shaped grooves 26a-26d (only one shown) for each of them suitably spaced along the length of the pattern plates at the same position in each plate. 27 are the pins (only one shown) that fit in these guide grooves 26a-26d and which pass through the groove 12 of the aforesaid holder 11 and are secured thereto. When the aforesaid pins are positioned so that they are on the same end of the guide grooves of each of the aforesaid pattern plates, the needle selecting projections 24a-24d of the respective pattern plates 23a-23d, as is clearly illustrated in FIG. 4, are arranged so as to be staggered in succession a distance equal to one pitch of the needles 3. In other words, when all of the pattern plates 23a-23d are

raised to their operative positions by positioning the pins in the left ends of all of the guide grooves, the needle selecting projections 24a-24d of these pattern plates will be arranged, as shown in FIG. 7 by means of broken lines, in staggered positions without overlap of any of said needle selecting projections. Hence, the foregoing needle selecting projections would be positioned such that each of the rear ends of the needle shanks 5 is vis-a-vis with respect to each of the needle selecting projections. This being the case, the same arrangement of needle selecting projections as has been set up in the operative position can be transferred in the lengthwise direction of the needle bed by changing a pattern plate in the operative position for one of the other pattern plates in inoperative positions. For example, in FIG. 7 the arrangement illustrated by means of solid lines is that in which pattern plate 23d has been raised to its operative position while pattern plates 23a-23c have been lowered to their inoperative positions, thereby making it possible to selectively advance every third needle. Now, if pattern plate 23d is exchanged for pattern plate 23b by lowering the former and raising the latter, the arrangement of the needle selecting projections capable of selectively advancing, as above, every third needle will be transferred to the right for a distance corresponding to two pitches of the needles. In like manner, a variety of transfers can be made as desired. The aforesaid engaging recesses 25a-25d are made to be arranged with suitable spacing in accordance with the order that the aforesaid needle selecting projections 24a-24b are arranged. As illustrated in FIG. 7, when the pin 27 is made to be positioned at the right end of each of the guide grooves 26a-26d, the needle selecting projections 24a-24d are maintained in their inoperative positions in which none of them are in engagement with any of the needles 3. On the other hand, when the pattern plates 23a-23d are moved to the right facing said figure and the pin 27 is made to be positioned at the left end of each of the guide grooves 26a-26d, the pattern plates 23a-23d rise somewhat as to maintain the needle selecting projections 24a-24d in their operative positions wherein they engage only the rear ends of the shanks 5 of the needles 3 that are participating in the knitting operation.

28 is a J-shaped supporting rack which constitutes a part of the reinforcing frame 1b. 29a-29d are push buttons, to the undersides of which are secured actuating plates 30a-30d, said actuating plates being fitted into openings 32a-32d and 33 which are provided respectively in the top plate 28a and the stepped portion 31 provided at the side plate 28c of the aforesaid supporting rack 28. Thus, said push buttons are provided in rows so as to be movable vertically at the upper side of said supporting rack 28. Between the push buttons 29a-29d and the supporting rack 28 springs 34a-34d are provided whereby the push buttons 29a-29d are constantly urged upwards.

35a-35d are openings that have been provided in each of the actuating plates, and, as shown in FIG. 7, they are provided with inclined guiding edges 36a-36d, holding portions 37a-37d at the lower ends of said guiding edges 36a-36d and locking portions 38a-38d at upper ends of said guiding edges 36a-36d. 39 is the journal plate affixed to the upper side of the bottom plate 28b of the aforesaid supporting rack 28. 40a-40d are L-shaped crank-shaped guide bars which are journaled so as to be rotatable in the aforesaid journal plate and which, extending in the direction of the advance and retraction of the needles 3, pass through the openings 36a-36d of one of the actuating plates 30a-30d and fit into one of the engaging recesses 25a-25d of the aforesaid pattern plates 23a-23d. 41a-41d are the springs provided between the supporting rack 28 and each of the aforesaid crank-shaped guide bars 40a-40d and act to urge the rotation thereof in a clockwise direction facing the FIGS. 2, 6 and 7.

As described hereinbefore, the push buttons 29a-29d are at all times pressed upwards by means of the springs 34a-34d and maintained in the position. When the push buttons are in this state, each of the crank-shaped guide bars 40a-40d, as shown in FIG. 7, being in engagement with the respective holding portions 37a-37d of the aforesaid actuating plates 30a-30d are prevented from rotating, and the pattern plates 23a-23d are held in their inoperative positions. When the push button is depressed, the aforesaid crank-shaped guide bars 40a-40d become released from their engagement with the holding portion 37a-37d, and by means of the rotative force of the aforesaid springs 41a-41d rotate and advance along the guiding edges 36a-36d of the actuating plates 30a-30d to the right facing FIG. 7, coming to a stop when they reach the right side edges of the openings 35a-35d. When the push buttons 29a-29d are released, the crank-shaped guide bars 40a-40d become engaged with the locking portions 38a-38d of the actuating plates 30a-30d and the rise of the push buttons 29a-29d are prevented. Hence, the push buttons 29a-29d are maintained in their depressed position, and the crank-shaped guide bars in their rotated and advanced positions, where they are both locked in operative positions. In this state the pattern plates 23a-23d that are coupled to the crank-shaped guide bars 40a-40d are pulled to the right, resulting in the needle selecting projections 24a-24d of said pattern plates being pulled up to their operative positions where they can engage the rear ends of the shanks of the needles 3 that participate in the knitting operation and at the same time becoming locked in this position. As described hereinabove, with the openings 35a-35d of each of the actuating plates 30a-30d being passed through by a single crank-shaped guide bar, the aforesaid push buttons can be, while independent of each other, locked cumulatively in their operative positions. Therefore, it is such that the pattern plates 23a-23d can also be readied cumulatively in the operative position independent of each other. Thus, it is possible to ready a plurality of optional pattern plates 23a-23d in the operative positions and by means of the combination of their needle selecting projections obtain a wide variety of selections in the arrangements of the needles.

42 is the locking and releasing plate attached as to be slideable in the lengthwise direction of the needle bed 2 to the inner side of the side plate 28c of the aforesaid supporting rack 23 by way of guide studs 44a, 44b mounted on the inner side of the side plate 28c of said supporting rack 23 and a pair of guide slots 43a, 43b provided in said locking and releasing plate through which said guide studs 44a, 44b pass through. This locking and releasing plate 42 is urged constantly to the right facing the FIGS. 2 and 6 by means of a spring 45 provided between said plate 42 and the supporting rack 23. At the bottom of the locking and releasing plate 42 are provided projections 46a-46d disposed on that side counteracting the aforesaid springs 41a-41d of each of the crank-shaped guide bars 40a-40d, and on one end of said locking and releasing plate is provided a bent portion 47.

When the aforesaid crank-shaped guide bars 40a-40d are locked in their operative positions, the respective projections 46a-46d of the aforesaid locking and releasing plate 42 come in contact with said crank-shaped guide bars 40a-40d as illustrated in FIG. 6. On the other hand, when the locking and releasing plate 42 is moved to the left facing the same figure, the crank-shaped guide bars are rotated counterclockwise against the action of the aforesaid springs 41a-41d. When the crank-shaped guide bars 40a-40d rotate as above the crank-shaped guide bars 40a-40d become released from their engagement with the locking portions 38a-38d, and thus the push buttons 29a-29d are pushed upwards by the springs 34a-34d. When the crank-shaped guide bars 40a-40d strike the left side edge of the openings 35a-35d and stop, the rise of the push buttons 29a-29d is terminated and

they are positioned in their inoperative positions, and the crank-shaped guide bars 40a-40d are in engagement with their holding portions 37a-37d of the actuating plates 30a-30d where they are to be held. The pattern plates 23a-23d are at this instant held in their inoperative positions. Precisely, by moving the aforesaid locking and releasing plate 42 to the left facing FIG. 6 the push buttons 29a-29d and the pattern plates 23a-23d that were locked in their operative positions are released simultaneously from their locked positions. When the release member 42 is released after completion of the above movement, it immediately reverts to its former position by means of the action of the spring 45.

43 is the linking member provided on the underside of the top plate 28a of the aforesaid supporting rack 23 so as to be movable in the lengthwise direction of the needle bed 2 by means of a pair of guide studs 50a, 50b mounted in said linking member and which pass through a pair of lateral guide slots 49a, 49b provided in said linking member 43. This linking member 43 is provided with a catch 51 which engages the bent portion 47 of the aforesaid locking and releasing plate 42, a slot 52 which is coupled with the bent portion 19 of the aforesaid link 20 and an indentation 53 in the middle thereof. When the aforesaid linking member 43 is moved to the left facing FIG. 6, the catch 51 of the linking member 43 and the bent portion 47 of the locking and releasing plate 42 engage and only the locking and releasing plate is moved to the left, thereby releasing from their locked states the push buttons 29a-29d which had been locked in their operative positions. On the other hand, when the linking member 43 is moved to the right facing FIG. 6, the slot 52 of the linking member 43 and the bent portion 19 of the link 20 engage and only the link 20 is moved to the right, thereby advancing the needle selecting member.

54 is the actuating shaft which is pivotally attached to the side of the cover 1a, and as shown in FIGS. 2, 3 and 6 that portion of the shaft protruding to the outside is provided therein with cutaway portions 55, whereas to that portion protruding towards the inside is secured an arm 57 having a pin 56 which fits the aforesaid indentation 53 of the linking member 43, whereby by turning said actuating shaft 54 the aforesaid linking member 43 is moved laterally. 58 is the operating handle provided at its extremity with a fork 59 that fits the aforesaid cutaway portions 55 of the actuating shaft. When the handle 58 is moved to the left, and the actuating shaft 54 is rotated counterclockwise, the aforesaid link 20 is moved to the right; while, on the other hand, when the handle 58 is moved to the right, the actuating shaft is caused to rotate clockwise, and the locking and releasing plate 42 is moved to the left.

When the hand-operated knitting machine of the present invention as described herein is used and fancy knitting is to be performed, if, to begin with, according to the selection made of the arrangement of the needles, a suitable number of push buttons are depressed and locked in their operative positions, then, as described hereinabove, the pattern plates 23a-23d coupled to the push buttons 29a-29d are readied in their operative positions, and their needle selecting projections 24a-24d are readied in a position in engagement with the rear end of the shanks 5 of the needles that participate in the knitting operations.

Next, by moving the handle 58 over to the left facing FIG. 6, the holder 11, through the intervention of the link 20 and the lever 15, advances as described hereinbefore, and the needles 3, which are in engagement with the needle selecting projections 24a-24b that have been readied in their operative positions, are selected and advanced simultaneously, thus making possible the selection and grouping, as desired, of the needles 3 that are to participate in the knitting operation. Needless to say, during the interim of the movement of the holder 11, the engaging recesses 25a-25d of the aforesaid pattern plates

23a-23d move together with the holder 11 while retaining their operative or inoperative positions alongside the aforesaid crank-shaped guide bars 40a-40d.

In case it is desired to change the arrangement of the needles 3 to be selected and advanced, if the aforesaid handle 58 is moved to the left facing FIG. 6, with the aforesaid push buttons 29a-29d and the pattern plates 23a-23d being released from their locked states by the locking and releasing plate 42, as described hereinbefore, the change is achieved very readily by repeating the above operations, i.e., by depressing the push buttons again according to the arrangement of the needles 3 that is desired.

Having thus described the nature of the invention what I claim is:

1. A hand-operated knitting machine comprising, in combination, an elongated supporting frame, a single elongated flat needle bed secured to said supporting frame, a plurality of needles arranged in a row in said needle bed capable of advancing and retracting at right angle to the lengthwise direction of said needle bed, each of said needles being provided with a shank projecting to the rear of said needle bed, and a needle selecting mechanism consisting of means for lowering the rear end of the shank of the needle perpendicularly to the upper flat surface of said needle bed when any of said needles is advanced to a somewhat more forward position for participation in knitting operations from its nonparticipating position, at least one needle selecting member mounted in said supporting frame to the rear of said needles capable of reciprocating movements parallel to the direction of the advance and retraction of said needles, said needle selecting member being of a length sufficient to act on all of the needles in said needle bed, means for reciprocating said needle selecting member, and a plurality of needle selecting projections arranged in a row at suitable intervals on said needle selecting member for selecting and advancing the needles when said needle selecting member is advanced by engaging the rear ends of the shanks of those needles participating in knitting operations that are disposed vis-a-vis with respect to said arrangement of needle selecting projections.

2. A knitting machine as defined in claim 1 wherein said needle selecting member consists of a holder reciprocably mounted on said supporting frame, a plurality of pattern plates held in said holder and having a plurality of needle selecting projections from the upper edges thereof arranged in a row at regular intervals, and the intervals of said needle selecting projections between each of said pattern plates being variable with reference to the pitch of the needles whereby the arrangement of needle selecting projections caused by the combining of said pattern plates is varied.

3. A knitting machine comprising, in combination, an elongated supporting frame, a single elongated flat needle bed secured to said supporting frame, a plurality of needles arranged in a row in said needle bed capable of advancing and retracting at right angle to the lengthwise direction of said needle bed, each of said needles being provided with a shank projecting to the rear of said needle bed, and a needle selecting mechanism consisting of means for lowering the rear end of the shank of the needle perpendicularly to the upper flat surface of said needle bed when any of said needles is advanced to a somewhat more forward position for participation in

knitting operations from its nonparticipating position, a holder reciprocably mounted on said supporting frame, a plurality of pattern plates held in said holder and having a plurality of needle selecting projections projecting from the upper edge of each of said pattern plates and arranged thereon in a row at regular intervals, said pattern plates being of a length sufficient to act on all of the needles in said needle bed, means for positioning said pattern plates normally in an inoperative position in which said needle selecting projections do not engage any of the rear ends of the needle shanks, means for reciprocating said holder, manually operable actuating members mounted in said supporting frame and of the same number as that of said pattern plates, means individually connecting said actuating members to one of said pattern plates and moving said pattern plates in an operative position wherein they are engageable with the rear ends of shanks of needles that are participating in knitting operations by actuating said actuating members that are connected to said pattern plates, means for locking said actuating members in their operative positions, thereby retaining in their operative positions said pattern plates which are connected to said actuating members, and means for simultaneously reverting said pattern plates to their inoperative positions as well as releasing said actuating members from their locked positions.

4. A knitting machine as defined in claim 3, wherein said manually operable actuating members are mounted in said supporting frame and each of them including a push button that effects ingress and egress into and from the upper surface of said needle bed in a direction perpendicular thereto.

5. A knitting machine as defined in claim 3, wherein said means for reciprocating said holder includes a rotatable shaft which is normally maintained in a neutral position and which also is connected to means for releasing the actuating members from their locked states, characterized in that the construction is such that when said rotatable shaft is turned in one direction from its neutral position said needle selecting member is advanced, whereas when said rotatable shaft is turned to the opposite direction from its neutral position said locking means is released from its locked state.

6. A knitting machine as defined in claim 3, wherein said needle selecting projections of the respective pattern plates are arranged in a row at regular intervals spaced a number of pitches of the needles equal to the number of plates used and, in their operative positions, are in staggered succession a distance equal to one pitch of the needles, whereby said needle selecting projections are positioned such that each of the rear ends of the needle shanks is vis-a-vis with respect to each of the needle selecting projections, said locking means being individually provided for each of said actuating members for locking each of said actuating members successively in its operative position, whereby the same arrangement of needle selecting projections are capable of being transferred to the lengthwise direction of said needle bed by exchanging the readied pattern plates in operative position for one of the other pattern plates in inoperative positions.
